Fig. 1.

Fig. 2.

Fig. 3.

FIGURE 1 is a front perspective view of a table, showing our new design;

FIGURE 2 is an end elevational view thereof; and

FIGURE 3 is a fragmentary perspective view of the leg structure.

The dominant features of the design reside in the portions shown in full lines in the drawing and are characterized by legs of angular cross section which are recessed in the side panels and spaced from the adjacent edges of the panel, substantially as shown.

The side of the desk not shown is the same in appearance as the side shown.

We claim:

The ornamental design for a table or similar article, substantially as shown and described.
